BATHTUB

Raymond K. Wibalda, Chicago, Ill., assignor to Borg-Warner Corporation, Chicago, Ill., a corporation of Illinois

Application December 26, 1952, Serial No. 22,888

Term of patent 14 years

(Cl. D4—4)

Fig. 2

To all whom it may concern:

Be it known that I, Raymond K. Wibalda, a citizen of the United States of America, and resident of Chicago, in the county of Cook and State of Illinois, have invented a new, original, and ornamental Design for a Bathtub, of which the following is a specification, reference being made to the accompanying drawing, forming a part hereof, in which:

Fig. 1 is a perspective view of a bathtub, showing my new design;

Fig. 2 is a front elevation thereof;

Fig. 3 is a vertical section taken along the plane of

Fig. 4 is a vertical section taken along the plane of line 4—4 on Fig. 1.

I claim:

The ornamental design for a bathtub, as shown.
